UNITED STATES PATENT OFFICE.

CHARLES H BROWN, OF BROOKLINE, MASSACHUSETTS, ASSIGNOR TO BERENICE BROWN,
OF BROOKLINE, MASSACHUSETTS.

SHOE.

1,249,318.

Specification of Letters Patent. Patented Dec. 11, 1917.

Application filed January 14, 1916. Serial No. 72,162.

To all whom it may concern:

Be it known that I, CHARLES H. BROWN, a citizen of the United States, and resident of Brookline, in the county of Norfolk and 5 State of Massachusetts, have invented an Improvement in Shoes, of which the following description, in connection with the accompanying drawing, is a specification, like characters on the drawing representing like 10 parts.

This invention relates to a novel construction of shoes.

This improved shoe is adapted to coöperate with and to correspond to the general 15 anatomical structure of the human foot.

And, having regard to certain State penal statutes, it is expressly disclaimed by the inventor that this novel shoe structure is a general cure for broken arches or flat-foot.

20 This shoe construction is not designed for crippled or malformed foot structures but was invented to provide a shoe having the qualities and attributes above-stated, which obviously are preventive rather than curative. As is well-known, the joints of the ball of the foot form an arch called the anterior or metatarsal arch. Under this arch there is a pad or cushion of flesh which, in walking barefoot, is pressed upon by the 25 bones of this arch. This spreads the bones apart and, when the weight is removed, they are immediately contracted by the flexible ligaments, fastening the bones together.

This action functions as a pump to insure 30 the blood circulation of the foot. As at present constructed, shoes are made from lasts the rear part of the ball of each of which is convexed. Consequently, the shoes formed thereon have the ball portions sub-

35 stantially concaved. And, as the natural foot structure operates normally in walking when the foot is presented to a flat surface, it follows that the effectuation of the natural functions of the human foot are thus 40 curtailed if not completely prevented. The

45 resultant physical disadvantages and dangers are too obvious and well-known to be enumerated. In this novel construction the inside of the shoe is shaped to permit the 50 natural cycle of operations of the forward arch of the foot in walking to be carried out.

Further, and more particularly, the shank of this novel shoe construction is improved. The bone formation of the human foot is 55 bridge-like. Extending from the tarsus or,

popularly speaking, the ankle, are the five bones which comprise the metatarsus. The phalanges, or toe bones, extend from the respective metatarsals. The arches of the bone structure are three—the metatarsal or 60 anterior, the longitudinal or long arch, and the transverse arch. Disregarding the pad of flesh, this bone structure has, substantially, three primary supports. The first is provided by the anterior or metatarsal arch 65 which is supported on the outer and inner sides, adjacent the first and fifth toe bones. A second support is formed by the end portion of the fifth metatarsal. This bone support is substantially in the line of the 70 little toe and is located to the rear thereof approximately at the middle of the foot and forms an abutment or base for one side on the transverse or middle arch. The third is the rear support of the foot structure 75 formed by the heel bone which is located toward the outer side of the foot. Along the bottom of the human foot and substantially toward its inner side extends the long cord, or "bow-string", which runs from the 80 forward edge of the heel bone to the ball of the foot at which point it has several attachments at different points just back of the metatarsal arch. Parallel with this long cord and very close to it run the main artery 85 and nerve of the foot. Adjacent this line, the inner side of the normal foot curves upwardly at a rather acute angle to the inner and unsupported side of the transverse arch. This novel shoe construction is made to follow 90 the natural configuration of the human foot in these regards. This long cord or ligament is subjected to hard strain as it functions as the anchorage for the two ends of the long arch. When the unshod foot is 95 placed upon the ground or floor, the tread base is at the outer portion and the long cord bears thereupon practically throughout its length.

The elevation of the heel tends to raise the 100 fifth metatarsal support from the level surface with which the structure is formed to contact in walking. This leaves that support without proper tread base and hence distortion, and strains are induced unless a 105 proper tread base is afforded. Further, the heel elevation raises the metatarsal arch supports from their natural tread surface and abnormal strains are there set up. As the inner side of the transverse arch of the in- 110

step is not directly supported, lacings or other shoe fastenings tend to turn the inner portion of the foot over and downward to meet the inside surface of the instep or shank of the shoe. It is therefore important to construct the shoe shank in substantial conformity to the shape of the inner side of the foot instep to prevent such foot distortion. The present shoe shank is generally defective in that it is not long enough, nor correctly shaped, nor does the usual narrow steel stiffener, anchored at the heel only, afford proper aid.

The disadvantages of the present shoe construction are overcome by affording a substantially unvarying tread base for the three supports of the foot structure and by constructing the inner surface of the shoe in conformity with the requirements of a normal foot as the heel rests upon a heel seat. The stiffening member in the preferred construction hereof begins well back in the heel seat where it is securely anchored. The forward end is anchored at a point generally less than an inch in front of the outside tread of the shoe, that is, the normal tread surface of the outersole presented to the walking medium. The forward end of the stiffener and the similar portion of a complementary element compose a wedge which serves the double purpose of supplying proper support to the anterior arch and of maintaining the outside tread of the shoe forepart. Further, the outer longitudinal portion of the shank stiffener is longitudinally curved to form a tread base, above the level of the ball portion, for the outer portion of the longitudinal arch. The transverse elements of this portion are substantially horizontal. The inner longitudinal portion is similarly curved to correspond to the contour of the longitudinal arch at the inner portion of the foot, the transverse elements of this stiffener inner portion being therefore upwardly inclined. Through this construction an unvarying tread base is assured for the heel, the bone supports of the anterior arch, and the end portion of the fifth metatarsal; while the inner side of the transverse is prevented from being drawn or "rotated" into an abnormal position.

The general object of this invention, therefore, is to produce a shoe which will practically and scientifically coöperate with the functions of the human foot.

A more specific object is to construct a shank member affording an unvarying tread base in a shoe. Other objects of this invention will more fully appear from the following description and the accompanying drawings and will be pointed out in the annexed claims.

In the drawings:

Figure 1 is a side elevation of a woman's shoe, the upper being broken away and

showing a partial longitudinal section through the sole;

Fig. 2 is a plan view of the bottom of the shoe, showing the shank member and complementary tread former in dotted lines;

Fig. 3 is a cross-sectional view on the line 3—3 of Fig. 2;

Fig. 4 is a plan view of the bottom of the shank former as applied to a woman's shoe;

Fig. 5 is a longitudinal section of a man's shoe embodying these improvements.

As is customary in this art, the upper 1, the innersole 2 and the welt 3 are sewed together while the outersole 4 and welt are likewise sewed together. And instead of the usual flat, narrow steel shank reinforcement tacked to the heel and with its floating forward end terminating back of the tread of the shoe at the ball, there is herein provided a novel shank structure, a selected form of which is shown. The novel shank reinforcing member 5 is shown, in Fig. 1, as embodied in the construction of a woman's shoe. This member 5, preferably formed of metal, steel being used, is substantially $\sim$ -shaped in section throughout its major portion and of a longitudinally arcuate form. The rear end 6 is flat and has the apertures 7 through which brads 8 or similar articles are passed to secure this end of the shank member 5 to the innersole 2. The forward portion 10 of the member 5 is slightly convexed upwardly and at its forward end is serrated, a pair of teeth 11 being preferably employed. The upward convexity of the portion 10 acts to preserve in the normal foot the natural condition, and to correct in an abnormal foot the lowered condition of the metatarsal arch. These teeth project upwardly and engage the under portion of the innersole 2, thus functioning to retain this end of the shank member in relatively fixed position. The doubly anchored shank member, thus curved, functions as a truss member for the shoe arch following the varying lines of the instep of the normal human foot and, because of its relatively fixed ends, movement between the forward and rear tread portions of the shoe is obviated.

This shank member is wider and longer in this embodiment than the usual shank iron of the present shoe. And, as shown in Fig. 3 of this selected embodiment, the outer longitudinal portion 12 of this shank member has its transverse elements substantially parallel to the horizontal surface of the toe portion of the shoe. The inner longitudinal portion 13 of this shank member has its transverse elements inclined upwardly. This arch commences at the rear of the ball portion 10, and, as shown in Fig. 1, extends well back into the heel portion of the shoe. The outer longitudinal portion 12 thus functions as a means to brace the outer portion of the shoe shank from the

heel seat to the forward tread and insures an unvarying tread base for the three primary bone supports of the human foot. The inner upwardly inclined portion 13 functions 5 as a similar member to retain the shank of the shoe in conformity to the contour and shape of the longitudinal arch at the inner portion of the foot instep.

A tread former 14, shown in dotted lines 10 in Fig. 2, is provided to form a forward extension of the inner tread of the shoe and at the same time to effect a rearward extension of the outside tread of the shoe. This tread former is preferably of leather or 15 fibrous substance and has substantially a triangular form in plan view. The apex of the generally triangular forward portion 10 of the shank member receives the similarly shaped portion of the tread former 14. This 20 former is preferably fixedly fastened to the forward portion 10 by means of rivets 15 passed through the apertures thereof. As is shown in Fig. 1, the tread former has a forward widened portion 17 while the thickness 25 of the former is greatly lessened at this portion 17. The portion of major thickness is that which forms the section adjacent the triangle apex. The shoe is thereby reinforced at that portion of the sole which 30 corresponds to the forward or metatarsal arch of the foot. Such construction effectively prevents any sagging of the inside tread of the shoe under working conditions and properly functions to support this forward or anterior arch, while at the same 35 time it substantially forms a graduated forward extension of the inside tread of the shoe. The outersole of the shoe is afforded a rearward tread extension through the co- 40 operation of the angled forward portion of the shank member and the thickened angled portion of the tread base 14. Such outside tread rearward extension 18 is best shown in Figs. 1 and 2.

In the application of these novel features 45 to men's shoes, which are usually of a heavier construction throughout, it has been found preferable to employ a complementary shank member or filler 19, Fig. 5. This 50 filler is, in this embodiment, shown as made of leather, though obviously fibrous or other suitable material may be employed. The filler has the same general J-shaped form as the shank member 5. When the filler is 55 employed, the forward portion 10 of the shank member is bent at 20 so that the forward portion 10 is offset to form a stop against which the lower or forward end 21 of the filler may abut.

This invention thus provides a shoe which 60 corresponds more closely to the general anatomical structure of the human foot. It is designed to be worn by the normal human foot and combines maximum foot support, 65 fit, comfort and durability. The inside

tread of the shoe is extended forwardly so that the metatarsal or anterior foot arch is properly and efficiently supported and prevented from sagging. The three supports of the bone structure are provided an unvarying tread base while the assured conformity of the inner side of the shoe to the natural shape of the inner side of the foot preserves the foot in normal state. The shank of the shoe is lengthened, strengthened 70 and formed the more scientifically to present a proper tread base and to fit and support the normal human foot.

It is to be understood that the construction disclosed herein is illustrative but not restrictive and that the same may be modified within the meaning and scope of the claims which follow.

Having fully described my invention, what I claim as new and desire to secure by 85 Letters Patent is:

1. In a shoe, the combination of a shank member having angularly disposed inner and outer surfaces, the inner surface meeting the outer surface in a line extending longitudinally of the shank member and forming an outwardly presented angle throughout the length of the disposed surfaces.

2. In a shoe, the combination of a shank member having angularly disposed inner and outer surfaces, the transverse elements of the outer surface being substantially horizontal, and the transverse elements of the inner surface being inclined upwardly, to provide the shoe with a reinforced support 95 for the foot along the inner and outer longitudinal portions of the shank of the shoe, the inner surface meeting the outer surface in a line extending longitudinally of the shank member and forming an outwardly presented angle throughout the length of the disposed surfaces.

3. In a shoe the combination of a shank reinforcing member, said shank member extending from the ball of the shoe to the heel portion, the member being secured adjacent each end to the sole of the shoe, and a complementary element secured to the forward portion of the shank member and shaped to form a reinforced support for the metatarsal 110 arch of the human foot.

4. In a shoe the combination of a metallic shank reinforcing member extending from the ball of the shoe to the heel portion, means for securing each end of the member 120 to the sole of the shoe, a non-metallic element secured to the forward portion of the shank member, said element being shaped to form a support for the metatarsal arch of the foot.

5. In a shoe the combination of a shank reinforcing member having longitudinally angularly apportioned inner and outer surfaces, the transverse elements of the outer surface being substantially horizontal and 130

the transverse elements of the inner surface being inclined upwardly, the forward end section of the member being unapportioned and forming a reinforced support for the 5 metatarsal arch.

6. In a shoe the combination of a metallic shank member having longitudinally angularly apportioned inner and outer surfaces, the forward end section of the member being 10 unapportioned, and a non-metallic complementary member shaped to conform to said apportioned surfaces and extending from a point adjacent the rear of the metallic shank member to said forward end section.

7. In a shoe the combination of a metallic shank member having longitudinally angularly apportioned inner and outer surfaces, the forward end section of the member being 15 unapportioned and offset, and a non-metallic complementary member shaped to conform to said apportioned surfaces and extending from a point adjacent the rear of the member and having its forward edge 20 abutting against a stop formed by said offset.

8. In a shoe the combination of a metallic shank member positioned between the inner and outer soles of the shoe, said member having longitudinally angularly apportioned inner and outer surfaces, the forward end section of the member being unapportioned, and a non-metallic element secured to 30 said section, said element having a portion shaped to conform to the forward end section of the member and extending therebeyond between the said soles and forming a reinforced tread support for the metatarsal arch.

9. In a shoe the combination of a metallic reinforcing shank member, a non-metallic complementary member conforming in shape to the shank member and placed thereon, and a non-metallic complementary tread member secured to the forward end of the 35 shank member so as properly to form reinforced supports for the longitudinal and metatarsal arches.

In testimony whereof, I have signed my name to this specification.

CHARLES H. BROWN.
